(57) **CLAIM**

The ornamental design for a swivel-top bead reamer handle, as shown and described.

DESCRIPTION

FIG. 1 is a perspective view of the swivel-top bead reamer handle, showing my new design;

FIG. 2 is a front end view of the swivel-top bead reamer handle of FIG. 1;

FIG. 3 is a rear end view of the swivel-top bead reamer handle of FIG. 1;

FIG. 4 is a top view of the swivel-top bead reamer handle of FIG. 1, the bottom view being a mirror image thereof; and, FIG. 5 is a perspective view of the swivel-top bead reamer handle of the present invention with an exemplary shaft and abrasive tip shown in broken lines.

The interior surfaces and depth of the swivel-top bead reamer handle shown in FIG. 2 are illustrated in broken lines and form no part of the claimed design. The broken lines of the shaft and abrasive tip of FIG. 5 depict environmental subject matter, showing use of the swivel-top bead reamer handle, and form no part of the claimed design.
